UNITED STATES PATENT OFFICE

109,118

DESIGN FOR A HAIR CURLER

Bertha A. Allen and James F. Allen,
Salt Lake City, Utah

Application October 12, 1936, Serial No. 65,269

Term of patent 14 years

To all whom it may concern:

Be it known that we, Bertha A. Allen and James F. Allen, citizens of the United States, residing at Salt Lake City, in the county of Salt Lake and the State of Utah, have invented a new, original, and ornamental Design for Hair Curlers, of which the following is a specification, reference being had to the accompanying drawing, forming a part thereof.

We claim:

The ornamental design for a hair curler as shown.

BERTHA A. ALLEN.
JAMES F. ALLEN.
